(57) **CLAIM**

The ornamental design for the pet disco ball toy, as shown and described.

DESCRIPTION

FIG. 1 is a perspective view of a pet disco ball toy;

FIG. 2 is a top view thereof;

FIG. 3 is a bottom view thereof;

FIG. 4 is a perspective view thereof;

FIG. 5 is another top view thereof; and,

FIG. 6 is another bottom view thereof.

The dashed lines in FIGS. 4-6 depicting a flat surface and rays of light exiting the ball depict environmental subject matter and form no part of the claimed design. The elliptical and slotted apertures on each half of the sphere are evenly spaced about their half of the ball.
